UNITED STATES PATENT OFFICE

1,943,826

LOCK

John Holtzman, New York, N. Y.

Original application March 12, 1925, Serial No. 14,980. Divided and this application December 24, 1930. Serial No. 504,515½

6 Claims. (Cl. 70—14)

My invention relates to locks of a type suitable for use upon swinging doors and my purpose being to enable the door to be locked and unlocked in the usual acceptation of these terms, 5 additional means being provided for fastening the door to the floor and thus preventing the door from being opened, in the event that the lock mechanism is disabled or destroyed, or for any reason is ineffectual in holding the door in 10 a predetermined fixed position.

More particularly stated I provide a fastening mechanism auxiliary to the door lock but connected therewith and normally controllable thereby, for the purpose of fastening and releasing the door under control of the lock, and yet adapted to fasten the door in a predetermined fixed position somewhat independently of the lock, so that the door will remain fastened in that position if the lock becomes disabled or 20 is otherwise rendered useless, as for instance if broken or mutilated by the efforts of a burglar.

This application is a division of my pending application Serial No. 14,980, filed March 12, 1925.

Reference is made to the accompanying drawing forming a part of this specification, and in which like reference characters indicate like parts throughout all of the figures.

Figure 1 is a front view, partly an elevation 30 and partly a section, showing my improved mechanism as applied to an ordinary door.

Figure 2 is a section on the line 2—2 of Figure 1, looking in the direction indicated by the arrows.

Figure 3 is a fragmentary front elevation of 35 the mechanism shown in Figure 2.

Figure 4 is a fragmentary sectional view of the lock, showing the means for operating the fastener.

Figure 5 is a section showing a turnbuckle 40 used as a means for adjusting the connection between the lock and the fastener.

A door is shown at 58 and is mounted to swing relatively to a jamb 59.

My lock appears at 60, and is mounted upon 45 and carried by the door. Associated with the lock 60 is a keeper 61, fixed upon the door jamb.

The lock is adapted to be actuated by both a 50 knob and a key, and is provided with a stem 62, extending through the lock casing and mounted to rock back and forth.

Fixed upon the stem 62, and thus located inside of the lock casing, is a lever 63 carrying a 55 pin 64 set in its free end, this lever and pin, as shown in Figure 4, being adapted to rock an-

gularly from a substantially horizontal position, as indicated in Figure 4 by full lines, into an oblique position as indicated in said figure by broken lines.

Journalled to the pin 64 is a link 65, extending downwardly through an opening 66 in the lower wall of the casing 60, and thus projecting slightly below the same. The lower end of this link is connected with a flexible member 67, preferably a wire cable, rope or string, this flexible member extending downwardly to a turnbuckle 68. Connected with this turnbuckle and extending downwardly therefrom is a flexible member 69, like the flexible member 67 and constituting practically a continuation thereof. The flexible member 67 is connected with the shoe 76, and when drawn upwardly may raise the shoe out of engagement with the floor.

A bracket 72, provided with a base 71, is secured firmly to the lower portion of the door, 75 and supporting a guide 70. The bracket carries a guide 70, and is provided with a ledge 73, disposed near the bottom edge of the door.

A pulley 74 is journalled upon the bracket 72, and engages the flexible member 59, this pulley 80 co-operating with the guide 70, as indicated in Figure 2.

The bracket 72 carries a pin 77, and journalled upon the same is a shoe 76.

The shoe 76 is provided upon its under face 85 with an undercut recess 79, in which is secured a pad 80, of rubber, or if preferred, an abradant material. A spring encircling the pin 77 engages the shoe 76 and the flange 73 respectively, the tendency of this spring being to press the shoe 90 76 downwardly, and thus to force the pad 79 downwardly against the floor. Thus the shoe 76 acts like a cam, and when against the floor can prevent the door from being opened, even if the lock be totally disabled.

With the various movable parts occupying the respective positions indicated for them in Figures 1 and 2, it is obvious that the lock 60 may be actuated after the manner of any other door lock, for the purpose of preventing the door 100 58 from being opened. If, however, the lock is so actuated as to release the door, the fastening consisting of the shoe 76 and parts immediately associated therewith is normally actuated at the same time. The result is, that the shoe 76 is 105 rocked upwardly upon the pin 77 whenever the lock 60 is properly actuated to permit the door to be opened.

Suppose, now, that the lock 60 is broken or 110 disabled, say by work of a burglar. In such

event the shoe 76 presses its pad 80 against the floor, and thus acts as a cam, which prevents the door from being opened.

Whenever it is desired to release the shoe 76 and also unlock the door, the ordinary turning of the key in the lock accomplishes both purposes simultaneously and at a single step.

Should it be required to maintain the shoe 76 in a raised position, a screw 81 in one of the sides of the bracket 72, may be placed in an opening 82 in the side of the shoe, for the purpose of enabling the shoe to be supported.

If desired, the shoe may be reversed or brought into the position indicated by broken lines in Figure 2. This done, the shoe operates to prevent the door from being closed.

I do not limit myself to the precise mechanism and described, as variations may be made therein without departing from my invention, the scope of which is commensurate with my claims.

Having thus described my invention, what I claim as new and desire to secure by Letters Patent is as follows:

25 1. The combination, with a key actuated lock, of a spring-impelled arcuate shoe pivotally supported on its top end to make frictional contact with a floor, means operated by said lock to raise the shoe, and said shoe being supported with a removable pintle pin permitting reversal of said shoe to retain the door in an open position.

30 2. The combination of a door lock having a rocking member which is caused to rock when said door is locked or unlocked, a bracket fixed upon the door adjacent its lower edge, a shoe pivoted on said bracket and having a curved surface adapted to grip the floor surface over which the door swings, said curved shoe surface being disposed eccentric to the axis on which said shoe pivots so that the frictional pressure of said shoe against the floor surface will be increased by pressure acting against the door, and a flexible adjustable element for connecting said rocking member with said shoe and key operated means operable from outside the door for controlling the movement of said shoe, said latter means permitting said shoe to lock upon the surface of the floor in any position of radial movement of the door, and rolling means connected with the door for directing the major portion of said flexible element to lie close to the door.

35 3. The combination of a door lock having a rocking member which is caused to rock when said door is locked or unlocked, a bracket fixed upon the door adjacent its lower edge, a shoe pivoted on said bracket and having a curved surface adapted to grip the floor surface over which the door swings, said curved shoe surface being disposed eccentric to the axis on which said shoe pivots, so that the frictional pressure of said shoe against the floor will be increased by pressure acting against the door, spring means tending to move said shoe into engagement with the floor surface, and flexible and adjustable means for connecting said rocking member with said shoe, and key operated means operable from outside the door for controlling the movement of said shoe, said latter means permitting said shoe to lock upon the surface of the floor in any position of radial movement of the door,

40 and rolling means connected with the door for directing the major portion of said flexible element to lie close to the door.

4. The combination of a door lock having a rocking member which is caused to rock when said door is locked or unlocked, a bracket fixed upon the door adjacent its lower edge, a shoe pivoted on said bracket and having a curved surface formed of compressible material, adapted to grip the floor surface over which the door swings, said curved shoe surface being disposed concentric to the axis on which said shoe pivots, so that the frictional pressure of said shoe against the floor surface will be increased by pressure acting against the door, and flexible and adjustable means for connecting said rocking member with said shoe, and key operated means operable from outside the door for controlling the movement of said shoe, said latter means permitting said shoe to lock upon the surface of the floor in any position of radial movement of the door, and rolling means connected with the door for directing the major portion of said flexible element to lie close to the door.

45 5. The combination of a door lock having a rocking member to be caused to rock upon the operation of the lock, a bracket secured upon the door adjacent its lower edge thereof, a shoe pivotally mounted on said bracket, a piece of yieldable material inserted in the lower part of said shoe to grip the floor surface over which the door swings, said shoe being constructed whereby the swinging movement of the door toward the open position tends to force said shoe against the surface of the floor and thereby tends to increase the pressure of said shoe against the floor, and adjustable and flexible means connecting said rocking member and the said shoe and key operated means operable from outside the door for controlling the movement of said shoe, said latter means permitting said shoe to lock upon the surface of the floor in any position of radial movement of the door, and rolling means connected with the door for directing the major portion of said flexible element to lie close to the door.

50 6. The combination of a door adapted to be swung toward open position, a bracket secured upon the door adjacent its lower edge thereof, a shoe pivotally mounted in said bracket and having side walls, a piece of yieldable material inserted in the lower part of said shoe to grip the floor surface over which the door swings, said shoe being constructed and arranged whereby the swinging movement of the door on its hinge, toward the open position thereof, tends to force said yieldable material against the floor surface and whereby the pressure of said shoe against the floor is increased upon the attempt to swing the same toward the open position thereof, and flexible and adjustable means to move said shoe into inoperative position and key operated means operable from outside the door for controlling the movement of said shoe, said latter means permitting said shoe to lock upon the surface of the floor in any position of radial movement of the door, and rolling means connected with the door for directing the major portion of said flexible element to lie close to the door.

JOHN HOLTZMAN. 145
